UNITED STATES PATENT OFFICE.

JOHN E. BELL, OF BROOKLYN, NEW YORK.

DAMPER.

1,311,436.

Specification of Letters Patent. Patented July 29, 1919.

Original application filed August 2, 1918, Serial No. 247,923. Divided and this application filed August 2, 1918. Serial No. 248,080.

To all whom it may concern:

Be it known that I, JOHN E. BELL, a citizen of the United States of America, and resident of Brooklyn, in the county of Kings and State of New York, have invented a certain new and useful Improvement in Dampers, of which the following is a true and exact description, reference being had to the accompanying drawings, which form a part thereof.

My present invention has for its object to provide simple and effective dampers or cut-off valves for conduits through which fluids at high temperatures are passed. My improved damper construction was especially devised for use in a plant in which a furnace system proper, such as a rotary kiln cement furnace system, has associated with it one or more waste heat boilers through which the hot products of combustion from the kilns are passed under certain conditions of operation, while under other conditions these products are diverted away from the boilers; and my improved damper or cut-off valve construction was primarily devised for use in opening and closing communication between the furnace system proper and the waste heat boilers of such a plant.

The various features of novelty which characterize my invention are pointed out with particularity in the claims annexed to and forming a part of this specification. For a better understanding of the invention, however, and the advantages possessed by it reference should be had to the accompanying drawings and descriptive matter in which I have illustrated and described preferred embodiments of my invention.

Of the drawings:

Figure 1 is a plan view of a portion of the cement kiln furnace and waste heat boiler plant with parts broken away and in section.

Fig. 2 is a partial section on the line 2—2 of Fig. 1.

Fig. 3 is a section taken similarly to Fig. 2, showing a portion only of the apparatus shown in Fig. 2, but on a larger scale and in greater detail.

Fig. 4 is a section on the line 4—4 of Fig. 3.

Fig. 5 is a partial section on the line 5—5 of Fig. 3, but with the damper removed.

Fig. 6 is a partial section on the line 6—6 of Fig. 3.

Fig. 7 is an elevation of a second damper part employed in conjunction with that shown in Figs. 3 and 4.

Fig. 8 is a section on the line 8—8 of Fig. 7.

Fig. 9 is an elevation of a modified form of damper.

Fig. 10 is a view taken similarly to Fig. 3, illustrating the use of the damper shown in Fig. 9.

Fig. 11 is an elevation of still another form of damper, and

Fig. 12 is an end view of the damper shown in Fig. 11.

In the furnace and waste heat boiler plant shown in Fig. 1, A represents the discharge ends of rotary cement kilns, each of which opens into a corresponding chamber B. From each chamber B, the hot gases issuing from the corresponding kiln may pass to the bottom of an adjacent stack chamber C through a port C', or may pass through a damper controlled outlet D to a bus channel E. The latter, in the plant shown, supplies a plurality of waste heat boiler units F. Partially cooled products of combustion drawn through the boilers F by the fans H, are further cooled before reaching the fans, by being passed through economizers G, which may serve as boiler feed water heaters. Above each stack chamber C rises the corresponding stack proper C². When the products of combustion are passed from the chamber B into the bus channel E the passage D is open, and the outlet through the stack chamber C is closed.

When the products of combustion entering the chamber B pass to the corresponding stack C² and out through the latter, the stack connection is open, and the outlet D is closed. No means by which the stack connection may be sealed, when conditions require, are disclosed herein, as such means form no part of the present invention. A simple and effective stack sealing arrangement for use in the furnace and waste heat boiler system illustrated is disclosed and claimed in my co-pending application Serial No. 247,923 filed of even date herewith.

The invention to which the present case pertains consists in special features of construction of the outlet D and in the means employed for closing and opening this outlet passage as conditions require. In the construction illustrated in Figs. 1 and 3, includ-

sive, each outlet passage D is formed of masonry with oppositely directed upwardly inclined bottom wall portions D', which meet at their upper ends and thus form a 5 restricted throat portion of the outlet passage. This throat, in the form shown, has flat bottom and side walls and an arched top wall. A groove D² is formed in the upper side of the bottom wall, and this groove reg- 10 isters at its ends with a slot or kerf D³ formed in the side and top walls of the restricted portion of the passage. The masonry forming the restricted portion of the passage D is encircled by a metallic armor 15 formed of two similar parts D⁴, which are bolted together at the bottom by bolts D⁵ connecting adjacent flange portions of the two parts D⁴. These flange portions and the bolts D⁶ may be, and are, shown as being 20 embedded in the masonry forming the bottom wall of the restricted portion of the passage D. The two parts D⁴ may advantageously be connected adjacent their upper portions by stays D⁶ connecting outer lugs or 25 ear portions D⁸ of the metal parts D⁴. The latter have inclined portions D⁷ which coöperate to form outwardly flared outer edge portions of the kerf D³.

To close the passage D a removable damper 30 I is employed. This is of plate like form, and when in place rests on the bottom wall of the groove D² and extends through the slot D³ at the sides and top of the passage. Advantageously, as shown, the damper is 35 formed with a metal rim portion I' and refractory body portion formed of fire brick mounted in the metallic rim. As shown, the rim portion I' comprises a one piece member forming the sides and top of the rim, and a 40 bottom portion I³, which has end portions secured to the outer rib or flange I² of the upper portion of the rim by bolts I⁴. The damper I is of a thickness a trifle less than the width of the kerf, to permit the easy in- 45 sertion and removal of the damper when this is necessary. To prevent leakage along the joints between the damper and the sides of the kerf D³ these joints are luted at their outer edges by moist clay or the like. The 50 effective luting of these joints is facilitated by the inclined surfaces D⁷ of the metal parts D⁴ and by the provision of the central rib or flange I² at the outer side of the metallic rim I' of the damper. Ears I⁵ secured 55 to the upper portion of the rib I² form means for connecting the damper to a suitable hoisting or transporting device somewhat conventionally illustrated at R in Fig. 2.

60 With the damper I in place, as shown in Figs. 3 and 4, the passage D is effectually closed. When it is desired to open the passage D the damper I is removed. It then becomes necessary to seal the kerf D³ in 65 order to prevent furnace gases from passing

outward or air from being sucked into the passage through the kerf. The kerf sealing device which I prefer to employ in conjunction with the removable damper I is shown in Figs. 6, 7 and 8. This kerf sealing device J, as shown, is shaped to fill the kerf D³ without projecting into the throat of the passage D. The device J differs essentially from the damper I only in having a portion cut away, and comprising an outer metallic 70 rim portion J', and an inner portion of refractory material, as fire brick, which is held in place by the rim portion. The rim portion is formed in three sections, a main section J', and two end sections J³. The end 75 sections are provided with extensions which overlap the outer rib J² of the main rim, and are secured to the latter by bolts J⁴. The rim J' is provided with ears J⁵ for connection to hoisting and manipulating mechanism. The kerf sealing device J is luted in place just as is the damper I.

In the modified construction illustrated in Figs. 9 and 10 the passageway D¹⁰ differs from the passage D, of the construction first 90 described, in that the kerf D³⁰ extends entirely across the walls of the passage, and the metallic armor D⁴⁰ at the edges of the kerf are entirely disconnected from one another and comprise flared luting or sealing 95 outer portions running all the way around the passage. The damper K is essentially the same in construction as the damper I first described, except that it is made about twice as high and is formed in the upper portion 100 with a passageway K'. In consequence, when the damper device K is in the position shown in Fig. 10 it seals the passage D³⁰, and when the damper K is lowered to bring its opening K' into register with the passage D³⁰ 105 the device K then serves the function of the separate part J in the construction first described. In either of its two operative positions the joints between the device K and the adjacent edges of the kerf D³⁰ are luted 110 with clay.

The modified construction shown in Figs. 11 and 12 differs from that shown in Figs. 9 and 10 essentially in that the damper KA is shortened in height and horizontally 115 elongated, and is moved horizontally to substitute its imperforate portion for the opening K¹⁰ or vice versa.

The damper constructions illustrated are simple and durable and possess the special 120 advantages for the uses specified, that with them leakage is reduced to a practical minimum, and difficulties due to the accumulation of flue dust are minimized.

The avoidance of leakage is of prime im- 125 portance, as the efficiency of the waste heat boiler system is greatly lowered by any considerable influx of air into the flues. The flue dust which is carried out of the kilns in large quantities has little opportunity to 130

5 clog up the passages adjacent the cut-off dampers with the downwardly inclined bottom walls at the opposite sides of the damper kerf. Furthermore, the passage adjacent this kerf, which is ordinarily 7 inches or so wide, may be readily cleaned through the kerf from time to time.

10 While in accordance with the provisions of the statutes I have illustrated and described the best form of my invention now known to me, it will be apparent to those skilled in the art that changes may be made in the form of my invention without departing from its spirit, and that some features 15 of my invention may sometimes be used to advantage without a corresponding use of other features.

Having now described my invention, what I claim as new and desire to secure by 20 Letters Patent, is:

1. The combination with a conduit formed with a transverse kerf in its wall and a plate like damper removably received in said kerf, said damper and conduit wall being formed 25 with surfaces coöperating to form an accessible luting material receiving groove at the outer edges of the joints between the side walls of the kerf and the damper.
2. The combination with a conduit formed 30 with a transverse kerf in its wall, of a damper for said conduit including a part adapted to substantially fill said kerf and

close the conduit, and another part adapted to substantially fill the kerf while leaving the conduit open, said damper parts and 35 conduit being formed with accessible surfaces coöperating to provide a luting material receiving groove at the outer edges of the joints between the side walls of the kerf and the damper.

40 3. The combination with a conduit formed with a transverse kerf in its wall and having the outer portions of the side walls of the kerf inclined away from the plane of the kerf and made accessible for luting, and a 45 plate like damper removably received in said kerf:

4. The combination with a conduit formed with a transverse kerf in its wall, and having the outer portions of the side walls of 50 the kerf inclined away from the plane of the kerf and made accessible for luting, and a plate like damper removably received in said kerf and formed with a metallic rim with a centrally extending rib on its top and 55 sides and a refractory filling.

5. A masonry conduit formed with a transverse damper receiving kerf, with the outer portions of the side walls of said kerf flared away from one another and made 60 accessible for luting, and having the walls of said kerf covered by a metallic facing.

JOHN E. BELL.
